(57) **CLAIM**

The ornamental design for a body mass index calculator, as shown and described.

DESCRIPTION

FIG. 1 is a perspective view of a body mass index calculator, showing my new design;

FIG. 2 is a top plan view thereof;

FIG. 3 is a side elevational view thereof;

FIG. 4 is a bottom plan view thereof; and,

FIG. 5 is a perspective view of the body mass index calculator of FIG. 1 shown in its environment.

The broken lines shown herein are for illustrative purposes only and form no part of the claimed design.

1 Claim, 5 Drawing Sheets

FIG. 1.

FIG. 2.

FIG. 3.

FIG. 4.

FIG. 5.

UNITED STATES PATENT AND TRADEMARK OFFICE
CERTIFICATE OF CORRECTION

PATENT NO. : Des. 493,190 S
DATED : July 20, 2004
INVENTOR(S) : Holland
